[57] CLAIM

The ornamental design for a chair, as shown and described.

DESCRIPTION

FIG. 1 is a perspective view from the front and to one side of the chair;

FIG. 2 is a side elevational view of the chair of FIG. 1, the opposite side being a mirror image thereof;

FIG. 3 is a front elevational view of the chair of FIG. 1;

FIG. 4 is a rear elevational view of the chair of FIG. 1;

FIG. 5 is a top plan view of the chair of FIG. 1;

FIG. 6 is a perspective view from the front and to one side of a second embodiment of the chair of FIG. 1, the sole difference being the addition of armrest members;

FIG. 7 is a side elevational view of the chair of FIG. 6, the opposite side being a mirror image thereof;

FIG. 8 is a perspective view of a third embodiment from the front and to one side of the chair of FIG. 1, the sole difference being the addition of armrest members;

FIG. 9 is a perspective view of a fourth embodiment from the front and to one side of the chair of FIG. 1, the sole difference being the addition of armrest members;

FIG. 10 is a perspective view of a fifth embodiment from the front and to one side of the chair of FIG. 1, the sole difference being the addition of armrest members; and,

FIG. 11 is a perspective view of a sixth embodiment from the front and to one side of the chair of FIG. 1, the sole difference being the addition of armrest members.
